UNITED STATES PATENT OFFICE

2,574,921

ROTARY PUMP

James P. Johnson, Shaker Heights, Ohio

Application October 26, 1948, Serial No. 56,490

6 Claims. (Cl. 103—160)

1

The present improvements relating generally as indicated to rotary pumps are more particularly concerned with rotary pumps having improved performance characteristics including high mechanical and volumetric efficiency and capable of high speed and high pressure operation.

In the most familiar types of rotary pumps, viz. the gear pump and the sliding vane pump, the former has the disadvantage of trapping fluid on the discharge side at the point of gear intermesh resulting in noisy operation and low mechanical efficiency particularly at high rotative speeds, and the latter has the disadvantage of excessive leakage at the sides and tips of the vanes particularly at high speeds, the tips of the vanes being in line contact or at the most in relatively narrow surface contact with the stator or rotor whereby to offer low resistance to leakage. Furthermore, such sliding vanes are subjected to considerable wear and generate excessive frictional heat in view of the high unit pressure contact of the tips thereof with the stator or rotor and the relatively great distance transversed by the tips while in such high unit pressure contact, viz. the perimeter of the surface engaged thereby multiplied by the revolutions per minute of the stator and rotor relative to one another.

Accordingly, it is one of the primary objects of this invention to provide a rotary pump of a form avoiding the aforesaid difficulties and capable of high pressure-high speed pumping operation at high mechanical and volumetric efficiency.

Another object of this invention is to provide a rotary pump in which a coupling member thereof reciprocably slides slowly relative to pump members coupled thereby in accordance with the eccentricity of said pump members and serves as a driving member between said eccentrically disposed pump members and forms with said members a variable volume cavity. In this way, a passage in one of said pump members establishes selective communication between such cavity and ports leading into the pump casing in which said pump members are rotatably supported.

Another object of this invention is to provide a rotary pump which essentially comprises an outer pump member having a running fit within the pump casing and an eccentrically disposed inner pump member within said outer pump member and rotatably supported by the pump casing, said members being connected in driving relation by a driving member having non-rotat-

2

able but transversely slidable connections with said members, such sliding occurring along relatively large surface areas whereby to minimize leakage or bypass therewith.

Another object of this invention is to provide a rotary pump of the character indicated in which the relatively small amount of such sliding consequently reduces wear and heat generation between the driving and pump members to a minimum. Furthermore, because of the large area contact between such driving and pump members, the unit pressure therebetween is relatively low further reducing wear and heat generation.

Another object of this invention is to provide a rotary pump in which the aforesaid driving member is reciprocably mounted in and on the inner and outer pump members respectively for varying the capacity of the cavities defined thereby with said pump members.

Another object of this invention is to provide a rotary pump including a universal coupling between the eccentrically disposed pump members thereof for permitting rotation of each pump member about its own axis.

Another object of this invention is to provide a rotary pump as aforesaid including novel means for varying the displacement thereof.

Another object of this invention is to provide a reversible rotary pump which may be operated in opposite directions without necessitating changing of any of the parts thereof.

Other objects and advantages will become apparent as the following description proceeds.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a cross section view of one embodiment of the invention taken substantially along the line 1—1, Fig. 2;

Fig. 2 is a cross section view taken substantially along the line 2—2, Fig. 1;

Fig. 3 schematically illustrates the operation of the pump of Figs. 1 and 2;

Fig. 4 illustrates the mode of operation of a pump similar to that of Fig. 1 except modified to omit one of the parts therein;

Fig. 5 is a diametrical cross section view of the

pump of Fig. 1 slightly modified to provide a square bore in the outer pump member and a square block portion on the inner pump member;

Fig. 6 is a cross section view of a still further modification taken substantially along the line 6—6, Fig. 7;

Fig. 7 is a cross section view taken substantially along line 7—7, Fig. 6;

Fig. 8 is a diametrical cross section view illustrating a pump casing and adjustable liner therein adapted to be used with the pumps illustrative for varying the capacity thereof; and

Fig. 9 is a cross section view similar to Fig. 8 illustrating a liner which is automatically adjusted in response to the pressure of the fluid delivered by the pump.

Referring now more particularly to the drawings and first to the pumps illustrative in Figs. 1 through 3, there is shown therein a pump casing part 1 formed with a bore 2 therethrough and ports 3 and 4 leading into such bore. At the opposite ends of said casing part 1 are cover plates 5 and 6 closing the ends of the bore 2 and thereby defining a cylindrical chamber, said plates being provided with bushings 7 and 8 or like bearings for rotatively supporting a rotor or inner pump member 9 therein with the axis 10 thereof eccentric relative to the axis 11 of such chamber formed in said casing. The aforesaid chamber may be lined if desired with a sleeve or liner 12 and end plates 13 and 14 fabricated from a suitable bearing material. Said sleeve 12 is fixed in casing part 1 and is slotted as shown to provide openings 15 and 16 respectively registering with the ports 3 and 4. Said casing part 1 and cover plates 5 and 6 are held together to form a unitary pump casing as by the bolts and nuts 17.

Within said sleeve 12 and surrounding said inner pump member 9 is a cylindrical outer pump member 18 having a close running fit with the pump chamber side and end walls as defined by the inner surface of said sleeve 12 and the inner faces of said end plates 13 and 14. Said outer pump member 18 is rotatable about an axis coinciding with the axis 11 of the casing bore 2 and eccentric relative to the axis 10 of said inner pump member 9. Said outer pump member 18 is formed with circumferentially spaced passages 19 therethrough each adapted to successively communicate with ports 3 and 4 through openings 15 and 16 in sleeve 12 during rotation of said outer pump member, such passages leading to the sides of a rectangular bore 20 in said outer pump member.

In the present case the inner pump member 9 is power driven through the splined shaft 21 projecting through cover plate 6 but obviously the outer pump member 18 may be power driven, if desired.

Non-rotatably fitted within said outer pump member 18 but slidable transversely therein is a tubular driving member 22 of rectangular cross section having openings 23 through one pair of its opposite walls communicating with two of the passages 19 and forming with the rectangular bore 20 two separate cavities each having communication with the other two passages 19 respectively.

Non-rotatably fitting within said driving member 22 is the rectangular block portion of inner pump member 9 having transverse slidable engagement therein along a path at right angles to the path of transverse sliding of said driving member within said outer pump member 18, the

opposed walls of said block portion forming two separate cavities within said driving members communicating with the remaining two passages 19 in said outer pump member through the openings 23 in driving member 22.

In this form of the invention the short sides of driving member 22 and the long sides of inner pump member 9 are substantially equal in order that the displacement of each of the four cavities of which such sides define movable walls during rotation of pump members 9 and 18 will be equal.

With respect to the operation of the Fig. 1 pump structure, starting at position I, Fig. 3, the cavity G progressively increases in volume to position V whereby during this portion of one revolution of pump members 9 and 18 through driving member 22 therebetween, the passage 19 associated with cavity G is in communication with intake passage 15 and port 3 in sleeve 12 and casing 1. Thereafter, from position V to position VIII and thence to position I, cavity G decreases in volume, its passage 19 during such rotation being in communication with discharge passage 16 and port 4 in sleeve 12 and casing 1. Cavity H similarly increases from minimum to maximum volume during rotation of said pump and driving members between the positions II and VI and decreases from maximum to minimum during rotation of said pump and driving members from positions VI to II, its passage 19 successively communicating with the intake and discharge ports of the pump. The other two cavities within outer pump member 18 similarly vary in volume during each revolution whereby to effect intake and discharge of fluid into and from four equal size cavities.

In the modification illustrated in Fig. 4, outer pump member 24 is provided with an axially extending rectangular bore 25 preferably square as shown with a driving member 26 non-rotatable but slidable transversely therein as shown. In this form of the invention said driving member 26 has a tongue and groove or like non-rotatable but transversely slidable connection with an inner pump member 27, such sliding being along a path perpendicular to the path of sliding movement of driving member 26 in outer pump member 24.

As shown, said driving member 26 divides the bore 25 into two separate cavities J and K and as evident from Fig. 4, cavity J increases in volume and cavity K decreases in volume from positions I to V and cavity J decreases in volume and cavity K increases in volume from positions V to VIII to I whereby fluid is successively drawn into and expelled from such cavities, such increase and decrease in volume of the cavities 60 having a predetermined relation to the porting in the pump as described in connection with the pump of Fig. 1. Said pump member 24 is formed with passages 28 leading into cavities J and K.

The pump illustrated in Fig. 5 is of the same construction as that of Fig. 1 except that the outer pump member 29 has a square bore 30 therein in which the tubular driving member 31 is non-rotatable and transversely slidable and that the inner pump member 32 has a square portion non-rotatable and transversely slidable in driving member 31, such sliding movements as in Fig. 1 being along paths perpendicular to one another. It will be noted that although the displacement of the four cavities defined between said pump and driving members are not equal

(the displacement of two opposed cavities being greater than the displacement of the other two opposed cavities) there will, nevertheless, be a uniform discharge during each revolution because the volume of the pair of smaller displacement cavities will increase and decrease between minimum and maximum drawing and expelling fluid through passages 33 in member 29 and openings 34 in member 31 and the volume of the pair of larger displacement cavities will increase and decrease between minimum and maximum drawing and expelling fluid through their associated passages 33 in member 29. Thus during each revolution, the delivery of the pump is the sum of the displacements of the four cavities. The operation of the pump illustrated in Fig. 5 will be evident from Fig. 3.

One of the reasons for making a pump as illustrated in Fig. 5 is to facilitate manufacture thereof and to obtain a better distribution of the metal of the pump members 29 and 32.

The pump illustrated in Figs. 6 and 7 essentially comprises a variation in the porting arrangement as compared with Figs. 1 and 5.

Referring specifically to Figs. 6 and 7 the pump casing comprises casing parts 35 and 36 forming a cylindrical chamber 37 therebetween preferably lined with end plates 38 and 39 and sleeve 40, all of bearing material. Rotatable within said chamber is an outer pump member 41 having a rectangular bore 42 therein (preferably square).

Also rotatable in said chamber and within said outer pump member 41 is an inner pump member 43 of rectangular cross section (also preferably square), said inner pump member being rotatable as in bushing 44 in casing part 35 about an axis eccentric of the axis of outer pump member 41 and provided with a splined drive shaft portion 45 projecting exteriorly of casing part 35. The square end of said inner pump member is formed with a cylindrical bore 46 and four radial passages 47 through the wall thereof leading to such bore.

Extending into bore 46 and having a running fit therewith is the cylindrical extension 48 of casing part 36 provided with a pair of axially extending passages 49 and 50 respectively leading from ports 51 and 52 in casing part 36 to transverse slots 53 and 54 registering with passages 47 in said inner pump member. As apparent from Fig. 6, each passage 47 will, during one revolution of inner pump member 43, successively communicate with slots 53 and 54 and thus with ports 51 and 52 of the pump.

Between said pump members 41 and 43 is a tubular coupling member 55 non-rotatably fitted over inner pump member 43 and within bore 42 of outer pump member 41 and having transverse sliding connections with said pump members along paths perpendicular to one another. Said coupling and pump members define between them four separate cavities, two opposed ones of which each have direct communication with one of two opposed passages 47 and the other two opposed ones of which each have communication with one of the other two opposed passages 47 through the opposed openings 56 through the opposed walls of coupling member 55.

Inasmuch as the mode of operation of the pump of Figs. 6 and 7 is the same as illustrated in Fig. 3 except for the disposition of the passages leading from the displacement cavities to the pump intake and discharge ports, no separate diagram has been included. As evident, the

cavities in alternately increasing and decreasing in volume during rotation of the pump and coupling members will accordingly draw fluid thereinto from the pump intake port and expel fluid therefrom into the pump discharge port.

In the several forms of the invention disclosed herein, the sliding movements are but a small fractional proportion of that present in conventional sliding vane pumps and furthermore large surface areas are provided to more effectively resist bypass or leakage between the several cavities in the pumps and to provide a driving angle considerably greater than that which will induce binding or cocking.

In Fig. 8 there is shown the basic elements of a variable volume pump comprising a pump casing 57 having an oblong bore 58 into which leads the ports 59 and 60 and within which casing bore a liner or sleeve 61 is fitted, said liner being provided with axially extending ribs 62 and 63 fitting into similarly disposed grooves 64 and 65 in said casing. Threaded into one of said ribs of said liner is a screw 66 rotatable but axially fixed in said casing as by a pin 67 engaged in a groove in the screw and locked as by a lock nut 68. As apparent, loosening of lock nut 68 and rotation of said screw 66 effects shifting of liner 61 in casing bore 58 so that the axis of said liner may be offset or eccentric any desired amount relative to the axis of the inner pump member (not shown) adapted to be disposed therein. Said liner 61 is of the same general construction as illustrated in Figs. 1 and 5 provided with slots 69 and 70 respectively registering with ports 59 and 60 and therefore any of the pump and driving member assemblies illustrated may be disposed therein. If desired, the grooves 64 and 65 may be provided with vents 71 and 72 to prevent trapping of fluid therein between the ends of the ribs and the bottoms of the grooves, such vents leading to the intake side of the pump casing. The liner 61 may obviously be of a form equivalent to liner 40 in Figs. 6 and 7.

It can now be seen that the capacity of a pump 45 may be readily varied between zero (no eccentricity between the pump members) and maximum (maximum eccentricity between the pump members).

In Fig. 9 is illustrated a variation of the pump 50 of Fig. 8 in which the sleeve 73, in response to the pressure of the fluid delivered by the pump and acting on the pump and driving members within said sleeve, is shifted transversely of the casing 74 to vary the eccentricity between the 55 pump members. One manner of accomplishing such action is to provide diametrically opposed extensions 75 and 76 on the sleeve fitting into recesses 77 and 78 and formed in the pump casing, one such extension 76 being adapted to 60 engage an adjustable abutment screw 79 threaded in said casing and extending into recess 78, said screw determining the maximum eccentricity and thus maximum delivery of the pump, and being locked in an adjusted position as by the 65 lock nut 80.

The other extension 75 has a recess in which is disposed a spring 81 compressed between said sleeve 73 and an adjusting screw 82 also threaded in casing 74 and extending into recess 77 for engagement by the sleeve 73 to determine the minimum eccentricity and thus the minimum delivery of the pump, said screw being locked in adjusted position as by the lock nut 83.

The casing 74 is provided with ports 84 and 85 and said sleeve 73 is provided with slots 86 and

87 respectively communicating with such ports and as indicated with reference to Fig. 8, said sleeve 73 may contain therein any of the pump and driving member assemblies herein disclosed. In Fig. 9 the sleeve 73 is shown in the position it assumes when delivering the maximum for which it is adjusted by screw 79. Under varied conditions of operation, said sleeve will shift back and forth transversely of its axis and at times the shoulder 88 thereof will engage screw 82 to provide a minimum delivery which may be zero if desired (axis of sleeve coinciding with axis of inner pump member) or any value between zero and maximum, the maximum being determined by the adjustment of screw 79.

Having thus described several embodiments of this invention it is now understandable that there is provided herein eccentrically disposed pump members one within the other which are non-rotatably connected together thus eliminating the high velocity tip speeds inherent in sliding-vane type pumps. Also, the provision of relatively wide surface contact and slow relative movement between the driving and pump members minimizes leakage therewith. The pumps herein disclosed also avoid the difficulties of gear pumps as previously stated. A still further feature of the present invention resulting from the relatively wide surface contact and relatively small distance of sliding between the driving and pump members reduces the wear and heating of such sliding surfaces to a minimum. Likewise, the wide bearing surfaces establish a driving angle considerably greater than one which would induce cocking and binding.

Briefly summarized, the present invention in rotary pumps comprises providing a casing in which pump members one within the other are rotatable about eccentrically disposed axes and in which a driving member between said pump members serves to non-rotatably connect said pump members together so that rotation of any of said members effects rotation of all of them and consequent pumping action as permitted by the angularly disposed transverse sliding connections between said driving and pump members. As apparent, this basic thought runs through all of the forms of the invention illustrated, such various forms, of course, to be regarded as merely typical and further modifiable without departing from the spirit of the invention.

In the preceding description and in the appended claims the word "pump" is to be construed in a liberal sense to include fluid pressure actuated motors as well, it being understood that fluid under pressure directed into one of the casing ports will drive the rotary assembly therein.

Other modes of applying the principle of the invention may be employed, change being made as regards the details described, provided the features stated in any of the following claims, or the equivalent of such, be employed.

I therefore particularly point out and distinctly claim as my invention:

1. A rotary pump comprising a hollow casing provided with intake and discharge ports leading thereto, an outer pump member and an inner pump member within said outer pump member supported for rotation within said casing about eccentrically disposed axes, said casing being provided at one end with a fixed cylindrical extension containing such ports and having a running fit within said inner pump member, said inner pump member extending exteriorly through the other end of said casing and being provided with

5 a passage successively communicating with such ports in such extension during rotation of said inner pump member, and a coupling member between said pump members having non-rotatable but transversely slidable connections with the latter, the paths of such slidable connections being angularly disposed relative to one another, said coupling member forming with said pump members a cavity having communication with such passage.

10 2. A rotary pump comprising a hollow casing provided with intake and discharge ports leading thereto, an outer pump member and an inner pump member within said outer pump member supported for rotation within said casing about eccentrically disposed axes, said casing being provided at one end with a fixed cylindrical extension containing such ports and having a running fit within said inner pump member, said inner pump member extending exteriorly through the other end of said casing and being provided with four equally spaced passages successively communicating with such ports during rotation of said inner pump member, and a coupling member between said pump members having non-rotatable but transversely slidable connections with the latter, the paths of such slidable connections being angularly disposed relative to one another, said coupling member forming with said pump members four independent cavities in communication with the respective passages in said inner pump member.

15 3. A rotary pump comprising a pair of casing parts defining a cylindrical chamber therebetween, a cylindrical extension in such chamber fixed to one of said casing parts and having an axis parallel to the axis of such chamber, said extension being formed with intake and discharge passages therein and with diametrically opposed transverse slots intersecting the respective passages, a rotatable inner pump member in such chamber extending exteriorly through the other of said casing parts and having a running fit over said extension and having at least one passage radially through the wall thereof which successively communicates with such slots during rotation of said inner pump member on said extension, a coupling member in such chamber having a non-rotatable but transversely slid- 20 able fit over said inner pump member and forming with the latter a cavity having communication with such last-named passage, and an outer pump member rotatable in such chamber about the axis of the latter and having a non-rotatable but transversely slid- 25 able fit over said coupling member along a path angularly disposed to the path of transverse sliding of said inner pump member and coupling member.

30 4. A rotary pump comprising a pair of casing parts defining a cylindrical chamber therebetween, a cylindrical extension in such chamber fixed to one of said casing parts and having an axis parallel to the axis of such chamber, said extension being formed with intake and discharge passages therein and with diametrically opposed transverse slots intersecting the respective passages, a rotatable inner pump member in such chamber extending exteriorly through the other of said casing parts and having a running fit over said extension and having four equally spaced passages radially through the wall thereof which successively communicate with such slots during rotation of said inner pump member on said extension, a coupling member in such chamber having a non-rotatable but transversely 35

slidable fit over said inner pump member and forming with the latter a pair of opposed cavities having communication with one pair of diametrically opposed passages, and an outer pump member rotatable in such chamber about the axis of the latter and having a non-rotatable but transversely slideable fit over said coupling member along a path angularly disposed to the path of transverse sliding of said inner pump member and coupling member, said outer pump member forming diametrically opposed cavities with said coupling member, and said coupling member being formed with diametrically opposed passages communicating such last-named cavities with the other pair of opposed passages in said inner pump member.

5. A rotary pump comprising a pair of casing parts defining a cylindrical chamber therebetween, a cylindrical extension in such chamber fixed to one of said casing parts and having an axis parallel to the axis of such chamber, said extension being formed with intake and discharge passages therein and with diametrically opposed transverse slots intersecting the respective passages, a rotatable inner pump member in such chamber extending exteriorly through the other of said casing parts and having a running fit over said extension and having at least one passage radially through the wall thereof which successively communicates with such slots during rotation of said inner pump member on said extension, a coupling member in such chamber having a non-rotatable but transversely slideable fit over said inner pump member, and an outer pump member rotatable in such chamber about the axis of the latter and having a non-rotatable but transversely slideable fit over said coupling member along a path angularly disposed to the path of transverse sliding of said inner pump member and coupling member, said outer pump member and said coupling member forming at least one cavity therebetween, and said coupling member being formed with a passage through the wall thereof communicating such cavity with the passage in said inner pump member.

6. A rotary pump comprising a pair of casing parts defining a cylindrical chamber therebetween, one of said casing parts being formed with an integral cylindrical extension in such chamber having an axis parallel to the axis of such chamber, said extension being formed with intake and discharge passages therein and with diametrically opposed transverse slots intersecting the respective passages, an inner pump mem-

ber journaled in the other of said casing parts about an axis coinciding with that of said extension and extending exteriorly of said pump, said inner pump member being provided with a rectangular portion in such chamber and a cylindrical bore having a running fit over said extension, said inner pump member being further provided with four passages radially therethrough leading from the respective faces of such rectangular portion and successively communicating with such slots during rotation of said inner pump member, a tubular coupling member of rectangular cross-section in such chamber having a non-rotatable but transverse slideable fit on one pair of opposed faces of the rectangular portion of said inner pump member and forming with the other pair of such opposed faces a pair of opposed cavities having communication with the one pair of passages in such other pair of opposed faces, and an outer cylindrical pump member journaled in such chamber for rotation about the axis of the latter and having a rectangular bore providing a non-rotatable but transversely slideable fit over said coupling member along a path at right angles to the path of transverse sliding between said inner pump member and coupling member, said outer pump member and coupling member forming a pair of opposed cavities therebetween, and said coupling member being formed with a pair of passages through opposed walls thereof communicating such last-named cavities with the other pair of passages in said inner pump member.
